HAIR COMB WITH MECHANICAL FINGERS

William H. Futterer, Key West, Fla.

Application July 11, 1957, Serial No. 671,294

4 Claims. (Cl. 132—145)

This invention relates to a comb which has been designed and constructed to temporarily clamp itself on the hair of the person whose hair is being cut, trimmed, curled or otherwise handled for treatment.

More particularly, a novel comb has been devised to assist the user thereof (barber, hair dresser or individual) to effectually employ the comb in a manner not heretofore possible. To this end, the teeth of the comb are widely spaced apart and are provided with pivotally mounted mechanical fingers. These fingers are so mounted and arranged that they can be swung out from the teeth in which they are normally sheathed and concealed to bridge the adjacent spaces. As the fingers come into play they gather and bunch the strands of hair and form spaced tufts, the free ends of which are then available to permit one to systematically and orderly hold and cut the same.

In carrying out the invention, in a preferred embodiment thereof, the back of the comb is provided at one end with a handle. Also, it is of hollow sectional construction and so designed and constructed that a spring-return push-pull rod is mounted for reciprocation therein, said rod having operating connection with adjacent actuating ends of the pivoted fingers, whereby all of the fingers may be simultaneously projected from their normally sheathed and concealed positions to their space-bridging hair gathering and clamping positions. To successfully accomplish this the push-pull rod is provided with a trigger which may be releasably locked in a position wherein the finger-operating rod functions to hold the fingers in the positions to which they have been moved for use.

Other objects, features and advantages will become more readily apparent from the following description and the accompanying drawing.

In the drawing, wherein like numerals are employed to designate like parts throughout the views:

Fig. 1 is a perspective view of a hair comb embodying the aforementioned mechanical fingers and the means for tripping and releasing the same.

Fig. 2 is a view, slightly enlarged, with parts in section and elevation, the view being taken on the plane of the line 2—2 of Fig. 1, looking in the direction of the arrows.

Fig. 3 is a further enlarged transverse or cross section taken on the line 3—3 of Fig. 2.

Fig. 4 is a detail view of the trigger and its keeper seat, the view being on the plane of the line 4—4 of Fig. 2.

Fig. 5 is a view partly in section and partly in elevation based on the showing seen in Fig. 1 with the cover plate of the so-called comb back removed.

Referring now to the views of the drawing the comb will be of suitable material, size and appearance with one end portion fashioned into an appropriate handle. The part of the body referred to as the "back" is denoted as an entity by the numeral 8. This is generally cylindrical in cross-section as seen in Fig. 3. One half portion 10 of the back is cut away as seen in Fig. 5 to provide end shoulders 12 and 14 and the removable cover section

2

16 is fitted in place between the shoulders as illustrated. The provision of suitably aligned holes 18 and sockets 20 (Fig. 5) serve to accommodate the fasteners 22 (Fig. 2). The opposed faces of the sections 10 and 16 are 5 grooved to provide a cylindrical-like chamber thus rendering the back hollow as before stated. In this cylinder or chamber the push-pull rod or plunger 24 is mounted as shown in Figs. 2 and 5 in particular. A coil spring 26 is attached at 28 to the right hand end of the rod and the other end of the spring is anchored securely in place as at 30. The purpose of the spring is to retract and return the push-pull rod to the normal ready-to-function position shown in Fig. 2. Longitudinally spaced notches 32 serve to receive the upper end portions 34 of the hair bunching and clamping fingers 36 therein. With reference to Fig. 2 it will be noticed that the stationary lateral longitudinally spaced teeth may be described as embodying an outermost tooth 38 having a recess or pocket 40 formed therein and an innermost tooth 42 having a similar recess or pocket 44. The intervening or main teeth, separately denoted by the numeral 46 are slotted, the slots being denoted at 48 and opening through the forward or leading edges of the respective teeth. These slotted teeth serve to house or sheathe the downwardly narrowed or tapering fingers therein. When the fingers are enclosed they are concealed. At this time, the intermediate portion of each finger bears against a stop web or shoulder 50 and the pointed end of the finger rests against a similar stop shoulder 52. Thus the movement of the teeth in a direction from right to left is limited so that the teeth are properly contained in the recesses or "pockets" of the respective comb teeth. By pivotally mounting the upper median portions 54 of the fingers they are allowed to 15 swing forwardly and rearwardly to assume the out-of-the-way or sheathed position illustrated in Fig. 2 or the projected space bridging positions seen in Fig. 5. When the fingers are projected to the last named position they not only bridge the wide space between the teeth but do so in an oblique angled manner to define a limited 20 pocket of the form seen at 56 in Fig. 5. It is in these confined spaces or pockets 56 that the strands of hair (not shown) are gathered, bunched and transformed into 25 the desired tufts.

With the individual tufts of hair divided, the barber, hair dresser or individual user may readily and without confusion cut, curl, or treat the tip ends of the strands in a step-by-step and therefore orderly manner.

There is a slot 58 (Fig. 4) formed in the bottom of the section 10 and this has notches 60 and 62 to accommodate the stem or shank 64 of the trigger. The trigger has a knob 66. With this construction the fingers may be retracted and sheathed to assume an out-of-the-way position or projected to assume their operating position, where they are locked, as it were, to clampingly hold the 30 comb on the user's hair.

The foregoing is considered as illustrative only of the principles of the invention. Further, since numerous modifications and changes will readily occur to those skilled in the art, it is not desired to limit the invention to the exact construction and operation shown and described, and accordingly all suitable modifications and equivalents may be resorted to, falling within the scope of the invention as claimed.

What is claimed as new is as follows:

1. For use by barbers, hair dressers, and individuals; a hair comb comprising a body having an elongated back provided with laterally directed longitudinally spaced combing teeth, said body having a sectional hollow back, a spring-return push-pull rod member reciprocable within the hollow portion of said back, the majority of said teeth being slotted lengthwise and each slotted tooth

having the additional function of a sheath, a finger sheathed and pivotally mounted in each tooth, and means operatively connecting the upper ends of said fingers to said rod member for operation in conjunction with said rod member.

2. The structure defined in claim 1, and wherein said rod member is provided with a trigger operating in a notched slot provided therefor at one end portion of said back.

3. The structure defined in claim 2, and wherein the slot in each tooth has spaced abutments providing stops, said stops serving to limit the pivotal movement of the finger in one direction.

4. For use by barbers, hair dressers, and individuals; a hair comb comprising a body having an elongated back provided with laterally directed longitudinally spaced combing teeth, and means carried by said teeth for gathering, bunching and temporarily holding the thus bunched strands of hair, whereby to permit the free ends to be cut, trimmed, curled or otherwise handled, said means being characterized by a plurality of mechanical

5 fingers, the latter being pivotally mounted, retractile and projectible and, when retracted being sheathed out of the way of the spaces between the teeth and, when projected, serving to bridge said spaces in a manner to clampingly embrace the strands of hair which have been gathered and bunched, said teeth being slotted lengthwise, each tooth constituting a sheath, each finger being blade-like, self-cleaning, and wholly folding into its sheathed and concealed position when not in use.
